DESIGN FOR A SCOOTER

Joseph C. Bancroft, New York, N. Y.

Application July 17, 1946, Serial No. 131,665

Term of patent 7 years

(Cl. D34—15)

To all whom it may concern:

Be it known that I, Joseph C. Bancroft, a citizen of the United States and resident of the city, county, and State of New York, have invented a new, original, and ornamental Design for Scooters, of which the following is a specification, reference being had to the accompanying drawing, forming part thereof, in which Fig. 1 is a side elevational view of a scooter, showing my new design, and Fig. 2 is a top plan view of the same.

I claim:

The ornamental design for a scooter, substantially as shown.

JOSEPH C. BANCROFT.
